MECHANISM FOR MANUFACTURING CYLINDRICAL CONTAINERS OUT OF FIBROUS MATERIAL SUSPENDED IN A LIQUID

Gottfried Held, Bern, Switzerland

Application July 22, 1936, Serial No. 92,052. Renewed April 12, 1939. In Switzerland August 2, 1935

3 Claims. (Cl. 92—58)

My invention relates to improvements in machines for the manufacturing of vessels such as pails, packing drums, barrels and the like out of fibrous material suspended in a liquid, whereby said manufacturing consists of a combination of the ordinary centrifugal method with a pressure-method specifically serving for the formation of the bottom of such a said container; and the objects of my improvement are, first, to provide a smooth surface on the inside of said container and a structurally more equal and tighter wall; second, to afford facilities for building the bottom of a container sufficiently strong; and, third, to afford means to reinforce such containers during the manufacturing with the aid of proper inserts into the walls and bottom of such containers.

I attain these objects by the mechanism illustrated in the accompanying drawing, in which—

Fig. 1 is a vertical section of the entire machine; Fig. 2 and Fig. 3 shows details—to a larger scale—of the machine.

The drawing illustrates a design-example of a mechanism for carrying through the method of manufacturing referred to above. The mechanism embodies a centrifuge with the base-plate 2 which suitably is detachably fastened to the vertical shaft 1. A bevelled gear aggregate 3 is driving the said shaft 1; the latter, however, also could be driven by way and means of a directly coupled electric motor. A cylindrical coarse-sieve 4—built up of a plurality of parts—is exchangeably inserted into a ring-shaped groove 2a of the base-plate 2, and the said parts of the sieve 4 are held together by means of a ring 5. A bottom-plate 6 possessing drain-holes 6a serves—in combination with a pressure-device—for the formation of the bottom of the container. Said plate 6 is sitting on top of the shaft 1 and also—by way of its bottom-rib—on the bed plate 2. The said pressing device possesses a vertical hollow shaft 7 which is vertically displaceable in a cylindrical guide 8 and is secured against turning by means of a key and keyway (Fig. 3). The shaft 7 is adapted as a rack possessing horizontal teeth 9 engaging with a pinion 10. The latter is mounted fast on the axle 11 of a hand-wheel 12. The axle 11 is turnable in a bush 13 which forms a single piece together with the guide 8. The latter is held by a yoke not illustrated. The shaft 7 is stepped off at 14, and an annular angle-collar 15 sits loosely on said stepped-off shaft. A helical spring 16, laid around said shaft, at one end abuts against said collar 15 and at the other end against the cage 17 of a ball-bearing 18. Said cage rests on the collar 19 of a cover 20, and the

shaft 7 has some play in said collar 19. The said part 20—in the fully drawn-out position of Fig. 1—covers the coarse-sieve 4. A bearing bush 22 is fastened to the bottom end of shaft 7 by means of a pin 21. Another pin 23 is held in said bush 22—in a manner not shown—and said pin 23 is turnable in ball-bearings 24. At its bottom-end said pin 23 possesses a flange 25 with which the perforated press-plate 26 is connected by means of screws. An angle-shelf collar 27 is screwed onto the lower end of the bearing bush 22 and forms—together with the flange 25—a labyrinth seal, schematically indicated at 28, against the loss of oil. The cover 20 is provided with an annular groove 29 on the bottom-side 15 and the top edge of the coarse-sieve 4 engages into said groove. The diameter of the press-plate 26 is such that the edge of the latter—with the shaft 7 rising after the manufacturing operation of a container has been finished—does not touch the inside wall of the said container.

The inner side of the coarse-sieve 4, as well as the top side of the bottom-plate 6, is lined with a detachable fine-sieve 30 consisting of one piece. The bottom side of the press-plate 10 also is 25 provided with a fine-sieve. Said fine-sieves may consist, e. g., of a wire-mesh in combination with a fibrous material, or of a wire-mesh lined on one side with a filter-cloth.

The hollow shaft 7—above the bearing bush 30 22—is provided with openings 31 for the passage of a suspension of fibrous material which is fed—out of a vessel which is not shown—through a flexible conduit, e. g., a hose, which also is not shown, into the said hollow shaft 7.

The manufacturing operation by way and means of the described mechanism is taking place as follows:

After the bottom-plate 6 and the coarse-sieve 4 have been mounted on the shaft 1 or, respectively, on the base-plate 2, the fine-sieve 30 is inserted and such a quantity of suspended fibrous material is filled into the form thus formed as is required for the formation of the bottom of the container. At this stage the ring 15, the spring 40 16, the cage 17, the cover 20 and the press-plate 26 occupy the position indicated by the dotted lines of Fig. 1. By turning now the hand-wheel 12, the shaft 7 with the press-plate 26 and the cover 20 is moved downward. At this juncture 45 50 the cover 20—as shown by the full lines of Fig. 1—comes to lie onto the top-edge of the coarse-sieve 4, while the press-plate 26 drops farther until it occupies the position shown by the full lines, whereby the filled-in material is

being pushed against the bottom-plate 6. The water escapes through the holes of the press-plate and through the sieve 4, while an eventual surplus of material is laterally squeezed upward 5 between the press-plate and the fine-sieve. With the press-plate 26 occupying the operating position, the spring 16 is stressed through the pressure of the heel 14 of the shaft 7 onto the ring 15. At this stage material is introduced into the 10 form by way of the hollow shaft 7 and the centrifuge is being put in operation. The bottom plate takes the press-plate—which is being pushed against the fibrous material—along and the pin 23 turns in the ball-bearings 24 of the 15 bearing bush 22. Similarly the coarse-sieve 4 carries the cover 20 with it which turns in the ball-bearing 18 around the shaft 7. The whole form, including the press-plate, thus is turning around the shaft 7, and the latter remains stationary. The suspended fibrous material is laying 20 itself in an equal layer against the fine-sieve 30, while the water is being drained off through channels and means not shown. In order to avoid that water be thrown into the operating space, one suitably provides an apron which is 25 detachably mounted on the base-plate 2 and which surrounds the coarse-sieve 4 at a certain distance. Said apron is not shown in the drawing. After a container has been finished, the 30 shaft 7 with the press-plate 26 is raised by means of the hand-wheel; the bearing bush 22 then pushes against the cover 20 and is taking the latter—together with the parts 15—18—along into the position shown by the dotted lines. The 35 shape produced then may yet be after-dried by introducing hot air into the form.

The design-example illustrated shows a circumferential depression 32 on the edge of the top-side of the bottom-plate 6 through which a reinforcing rib is produced on the outside of the container-bottom. Said depression, however, also may be dispensed with.

Containers which must be built structurally strong may be reinforced during the manufacturing operation by means of inserts of wood, wire, wire-mesh and the like.

In order to produce containers of different size, one only needs to correspondingly exchange the parts 2, 4, 6, 20, 26 and 30.

50 The pressing device, instead of being adapted independently from the centrifuge as in the example of design chosen, also could be incorporated in the centrifuge itself.

The technical advance embodied in the described method and procedure consists in the 55 combination of the advantages of the centrifugal method—quicker and cheaper operation and obtaining a more equal structure of the side-walls of the containers as compared with the compressed air-method—with the further advantage of producing a much stronger and more resistant container-bottom by way and means of the pressure-method as compared with the methods applied heretofore. The method and procedure described is not limited by the size of the con-

5 tainers to be manufactured, so that also packing drums, barrels and the like may be made by ways and means of the mechanism described.

What I claim and desire to secure by Letters Patent is:

1. A machine of the character described, comprising a mechanically operated centrifugal part and a manually operated pressure assembly; the centrifugal part comprising a rotative shaft, a base plate detachably fastened to the latter, an 10 exchangeable perforated circular mould riding on the said plate, an individual and detached perforated bottom plate also riding on the said plate, and an exchangeable and detached top plate riding on the top of the said mould and possessing 15 a central circular opening; the said pressure assembly comprising a hand-wheel, an axle rotatable in a bush, a pinion keyed to the said axle, a stationary guide in the form of a hollow axle integral with the said bush, a hollow shaft segmentally adapted as a rack which may be raised 20 and lowered inside the said guide by means of the said rack and pinion, means fastened to the center portion of the said shaft for the purpose of exerting a steady pressure against the said top 25 plate of the centrifugal part, the lower portion of the said shaft projecting through the said opening of the latter plate and possessing a plurality of holes for the purpose of admitting pulp fed through the said shaft into the space enclosed 30 by the said mould, and a bottom assembly pinned to the said shaft and comprising, in its turn, a bottom-most perforated pressure plate, a flange screwed to the latter, a plurality of ball-bearings, a housing for the latter, a pin held fast in the 35 said housing and rotatable on the said ball-bearings, and a cap screwed onto the said housing which, together with the said flange, forms a labyrinth seal for the lubricating oil; the whole in such an operative association that the spinning 40 of the said centrifugal part is building the wall of the container while the bottom of the latter simultaneously is moulded under pressure applied axially by the said pressure assembly.

2. A machine as claimed in claim 1 wherein 45 the base plate of said centrifugal part is provided with a peripheral recess and said centrifugal part further comprises a loose and exchangeable sectional fine-mesh wire-cage as an inside lining for the said bottom plate and top plate and the said perforated mould; the said recess being provided for the purpose of incorporating a reinforcing circumferential rib into the bottom of the container to be manufactured, and the fine-mesh wire-cage serving for the purpose of retaining 55 the pulp in its proper location.

3. A machine as claimed in claim 1 wherein is further provided a loose and exchangeable sectional fine-mesh wire-cage as an inside lining for the said bottom plate and top plate and the said 60 perforated mould, and an insert or lining of fibrous and permeable material or of filter-cloth for the said wire-cage.
